UNITED STATES PATENT OFFICE.

CHARLES H. BALDWIN AND ALONZO R. SHUTE, OF PORT JEFFERSON STATION, NEW YORK.

COLLAPSIBLE BED-SPRING.

1,211,041.

Specification of Letters Patent.

Patented Jan. 2, 1917.

Application filed May 28, 1915. Serial No. 31,027.

To all whom it may concern:

Be it known that we, CHARLES H. BALDWIN and ALONZO R. SHUTE, citizens of the United States, residing at Port Jefferson Station, Long Island, in the county of Suffolk, State of New York, have invented certain new and useful Improvements in Collapsible Bed-Springs; and we do hereby declare the following to be a full, clear, and exact description of the invention, such as will enable others skilled in the art to which it appertains to make and use the same.

This invention relates to a collapsible bed spring.

An object of the invention resides in the provision of a device of this character which may be readily disassembled and the parts conveniently packed for shipping.

A further object of the invention resides in so constructing the device that the spring portion may be subjected to various degrees of tension when the device is assembled.

With these and other objects in view, such as will appear as the description progresses, the invention comprises the combination and arrangement of parts as set forth in and falling within the scope of the appended claim.

Referring to the drawing: Figure 1 is a side elevation of the device. Fig. 2 is a bottom plan view thereof. Fig. 3 is a vertical sectional view on line 3—3 of Fig. 1. Fig. 4 is a longitudinal vertical sectional view through the push bars.

Referring to the drawing wherein like parts are indicated by like characters throughout the several views:—In the embodiment of the invention shown in the drawing we have provided a frame which consists of end bars 1 having reinforcing strips 2 secured thereto, the end bars being of greater widths than the reinforcing strips. Secured to these end bars 1 and extending between the same and the reinforcing strips is a spring member 3.

In order that the end bars may be held in their proper positions, rigidly, and the spring member subjected to the proper tension the end bars 1 are provided with holes 4 adjacent their upper edges and with relatively smaller spaced holes 5 adjacent their lower edges. Loosely and removably mounted in the holes 4 are push bars 6, the ends of which are adjustably secured together by

turn buckles 7 having openings 8 therein for the insertion of a handle. Slidably mounted on the push bars 6 are collars 9 to which are secured brace rods 10 which extend through the holes 5 in the end bars and have nuts 11 adjustably and detachably mounted thereon. The ends of the push bars are provided with screw threads 12 on which adjusting nuts 13 are mounted. The end bars 1 are provided with sockets 14 for engaging the end of the bed so as to hold the device in place.

In assembling the device the spring member 3 is laid out flat with the end bars attached to each end thereof. The push bars with the turn buckles between them are inserted in the holes 4, the ends of the brace rods 10 are inserted in the holes 5 and the nuts 11 engaged therewith. The turn buckles are then operated to force the push bars apart and consequently stretch the spring member. When the proper tension is attained the nuts 13 may be adjusted to draw the brace rods 10 so that the end bars will be rigidly held in their proper positions.

It is to be noted that after the springs have been stretched by the push bars that the end bars 1 may be drawn into such positions that they will extend at right angles to the push bars and it will be necessary to force these end bars into this position because of the fact that the pivotal points lie in alignment with the push bars and further because of the fact that the force which is applied to the end bars is applied by the springs and above the pivotal point. It is the presence of the adjusting nuts 13 that permits the easy assembly of the parts and permits the brace members 10 to be drawn into such positions that the push bars will be maintained in the holes 4 and prevented from displacement therefrom.

It will thus be seen that we have provided a very simple collapsible bed spring which may be easily assembled or disassembled and when assembled will be rigid and the spring member under the proper tension.

While we have illustrated and described a particular embodiment of our invention we have merely done so for the sake of convenience and do not wish to be limited to that particular embodiment as it is obvious that numerous changes may be made within the details of construction thereof without

in any way departing from the spirit of the invention or exceeding the scope of the appended claim.

What we claim is:

- 5 In a collapsible bed spring, the combination with a pair of flat end bars, of a spring member secured to and extending between the upper edges thereof, adjustable push bars extending between the end bars adjacent to
- 10 the upper edges thereof, brace rods adjustably connected to the end bars adjacent to

the lower edges thereof and adjustably connected to the push bars and means for securing the braces in their adjusted positions.

In testimony whereof, we affix our signatures, in the presence of two witnesses.

CHARLES H. BALDWIN.
ALONZO R. SHUTE.
